UNITED STATES PATENT OFFICE.

RICHARD JAMES SMITH, OF DUBLIN, IRELAND.

TORPEDO-NET.

1,242,611.

Specification of Letters Patent.

Patented Oct. 9, 1917.

Application filed April 6, 1917. Serial No. 160,079.

To all whom it may concern:

Be it known that I, RICHARD JAMES SMITH, a subject of the King of Great Britain, residing at 36 Fitzwilliam Place, Dublin, in the county of Dublin, Ireland, have invented certain new and useful Improvements in Torpedo-Nets, of which the following is a specification.

My invention relates to improvements in 10 torpedo nets and has for its object to provide means by which a resilient resistance to an oncoming torpedo is produced when such torpedo strikes either the outer or inner open portions of the net or both, in 15 order to gradually reduce or destroy the momentum of the torpedo and in such a manner that the danger of the torpedo firing pin striking the net is reduced to a minimum.

For the foregoing purpose, the said 20 improved torpedo net comprises a system of V-shaped netting having open or closed entrances to each V-shaped entrance, and adapted to lie in or about in the horizontal or vertical planes. Said netting is suitably 25 braced and is adapted to be suspended from its top portions by means of hooks or other suitable and known devices designed for the suspension and lowering and raising of torpedo nets which are held out at a suitable 30 distance from the ship's hull or sides. Said V-shaped net may be made in detachable sections of a suitable size adapted to be connected together by any suitable means.

An example of said torpedo net constructed 35 in accordance with my said invention, and showing some but not all of the reinforcing braces or stays, is illustrated in the accompanying drawing and more fully described hereinafter, the same reference numbers being 40 used for the same parts throughout:

In the drawings, Figure 1 shows a side elevation of said net, and Fig. 2 shows an end elevation in part. Fig. 3 shows a plan view of a section or part of said V-shaped 45 net.

The V-shaped net 1 is cut away at its inner end or apex 2 and is adapted to form an open space 3, the net being tapered to its opposite end 4 to form an opposite and 50 larger opening 5 or open space 5 adapted to receive an on coming torpedo which drives into any one of the open V-shaped nets 1 which are so tapered from the smaller opening 3 to the larger opening 5 as to cause the 55 torpedo to be wedged tighter the further it enters the open and V-shaped net so that a

more or less resilient resistance is offered to the torpedo until its momentum is destroyed. In case the torpedo should drive in as far as the opening 3, its firing pin would not meet 60 with any resistance. Said V-shaped net is fixed at 6 to two upper and opposite supports or cables 7, and is fixed at 8 to two lower and opposite supports or cables 9. The smaller end of each V-shaped net at 7 65 extends a convenient distance beyond the cables or supports 7 and 9, as shown, the outsides of the net being braced or reinforced by suitable and flexible wires or stays 10 which are fixed to the top support 7 and 70 to the corresponding bottom support 9 which latter supports are braced by suitable stays such as T-iron stays 11, as shown. The flexible wires or stays 10 and the V-shaped net 1 at 6 and 8 are fixed rigidly together and 75 to the corresponding top and bottom supports or cables 7 and 9 by any suitable means such as by brazing together or clamping together by suitable clamps, and the T-iron stays 11 are fixed at 12 and 13 in a similar 80 manner. If necessary, the nets 1 may be reinforced by suitable wires 14 which may be suitably fixed to transverse braces connecting the top and bottom pairs of supports 7 and 9, these transverse braces not 85 being shown. Fig. 2 shows a method of connecting the netting and braces to the pair of upper and lower supports or cables 7 and 9, but any convenient system of bracing may be used for the whole apparatus and 90 in such a manner that each V-shaped net or the opening 3 and 5 therein are kept in the approximately correct position, as shown, and so that the openings 3 cannot be enlarged to the extent of letting a traveling 95 torpedo pass through; and the angle at 15 of each V is made suitable to produce the best results in trapping and gradually bringing to a halt an on coming torpedo. The whole apparatus when in operation is suspended 100 out from the ship's side or hull at a suitable distance therefrom and to a suitable depth in the water and above the water by any suitable and known type of supports or lowering and raising device used for manipulating torpedo nets by making suitable connections to said pair of upper supports or cables or cross braces therefrom. When 105 in position in the water said V-shaped net is preferably hung in the vertical plane as 110 shown in plan view in Fig. 3. The open ends at 3 may be braced by connecting to

spaced and transverse ropes running parallel.

In a modification, the inner and open ends 3, which are arranged nearest to the ship's 5 hull, are closed as shown in dotted lines at 16 so that the V-shaped net is made in one continuous section which is suitably braced. Said V-shaped net in any of its forms may be made in detachably connected sections 10 which may be fixed together in any suitable manner such as by clamps and bolts engaging each adjacent end of each section of net in suitable positions.

The main and distinguishing feature of 15 my said invention lies in having a V-shaped net whose outer ends at 5 and whose inner ends at 3 are open or whose inner ends at 16 are closed in a modification, and which V-shaped net in either form is suitably 20 braced, supported and suspended so as to normally assume the V-shapes shown and so as to trap and offer a resilient resistance to a traveling torpedo and so as to assist in preventing an explosion of the latter.

25 Having described my invention, I claim:

1. A torpedo guard comprising pairs of

upper and lower cable supports, and a series of wedge shaped nets with their V ends secured to the upper and lower outer cables 30 and their inner ends secured to the upper and lower inner cables thereby forming tapering open ended pockets having resilient sides to reduce the momentum of a torpedo and so render it inoperative.

2. A torpedo guard comprising pairs of upper and lower cable supports, series of wedge shaped nets with their pointed ends extending between the upper and lower outer cables and their inner ends between 40 the upper and lower inner cables, means for securing the pointed ends of the series of nets to the outer cables, and devices for securing the inner ends of the nets to the inner cables so that the nets form a plurality 45 of tapering open ended pockets having resilient sides so as to reduce the momentum of a torpedo to render the same inoperative.

Signed by me this 9th day of March, 1917.

RICHARD JAMES SMITH.
